(57) **CLAIM**

The ornamental design for an electric tooth cleaning device, as shown and described.

DESCRIPTION

1. Electric tooth cleaning device

The design relates to an electric tooth cleaning device, in particular a vibrating tooth cleaning device for the simultaneous cleaning of several teeth, in particular all the teeth of a human user; FIG. 1.1 shows an overall view from the front; FIG. 1.2 shows an overall view from the rear; FIG. 1.3 shows an overall view from the left side; FIG. 1.4 shows an overall view from the right side; FIG. 1.5 shows a top view; FIG. 1.6 shows a bottom view; FIG. 1.7 shows a perspective view.
